Minn., a corporation of Minnesota

Application August 14, 1930, Serial No. 475,368

10 Claims. (Cl. 226—18)

My invention relates to devices for and methods of packing articles in boxes and has for an object to provide a device and method whereby the articles may be rapidly packed in the boxes.

8 Another object of the invention resides in providing a device and method whereby the articles may be packed in open ended boxes having flaps for the closure thereof.

10 A still further object of the invention resides in providing a device whereby the articles may be packed in relatively flat boxes open at the narrowest ends thereof by insertion of the article into such end of the box.

15 A feature of the invention resides in the method of packing articles in boxes which consists in employing a cardboard support on which the article is mounted and in simultaneously forming runners on said support and inserting the support into the box.

20 An object of the invention resides in the method of packing fabric articles in boxes which consists in holding the box upon a planiform base, in placing the article upon the base, in placing a cardboard support upon the article, in folding 25 the article over the support, and in thereafter sliding the support with the article therein along said base and into the box.

Another object of the invention resides in providing a device for packing articles in boxes including a base together with abutments for supporting a box with the bottom thereof overlying said base.

35 A still further object of the invention resides in providing a bar extending across the open end of said box above the same and mounted upon said base, and in attaching to said bar a U-shaped spring clip for engagement with the top flap of the box to hold the same in open position.

40 Another object of the invention resides in attaching to said abutments spring fingers for engaging the end flaps of the box for holding the same in open position.

An object of the invention resides in forming 45 said base with a depression for the reception of the bottom flap of the box and providing said base with a member overlying said depression to engage the extreme end of the lower flap to hold the same in place.

50 Another object of the invention resides in scoring the cardboard support along spaced parallel lines to form an inner and an outer flange at each side of the support.

A still further object of the invention resides 55 in providing guides along said base for engage-

ment with the flanges of said support to guide the support in its movement toward the box.

A feature of the invention resides in disposing in proximity to said guides formers for retaining the inner of the flanges of said cardboard support perpendicular to said support. 60

An object of the invention resides in providing other formers cooperating with said first named formers for folding the outer of the flanges of the support back upon the inner of the flanges 65 thereof.

Another object of the invention resides in constructing the outer flanges of the support of a width equal to twice the width of the inner flanges to cause the body of the support to lie midway 70 between the walls of the box.

Another object of the invention resides in providing a plunger for reciprocating the support with the garment attached thereto along said guide to form the runners thereon and to insert the same 75 into the box.

Other objects of the invention reside in the novel combination and arrangement of parts and in the details of construction hereinafter illustrated and/or described. 80

In the drawings:

Figs. 1, 2 and 3 are plan views of my invention showing the parts in various positions.

Fig. 4 is a cross sectional view taken on line 4—4 of Fig. 1 and drawn to a larger scale. 85

Fig. 5 is a plan view of a portion of the structure shown in Fig. 1 drawn to a larger scale.

Fig. 6 is a fragmentary longitudinal sectional view taken on line 6—6 of Fig. 5.

Fig. 7 is a longitudinal sectional view taken on line 7—7 of Fig. 1 and drawn to the same scale as Figs. 4 and 5. 90

Fig. 8 is an elevational view similar to Fig. 7 viewed from the same side as Fig. 7.

Fig. 9 is a cross sectional view taken on line 9—9 of Fig. 5 illustrating a support with the runners thereof completely formed. 95

Figs. 10 and 11 are fragmentary views similar to Figs. 4 and 9 showing the support partly formed and taken on lines 10—10 and 11—11 of Fig. 5 respectively. 100

Fig. 12 is a perspective view of one form of box adapted to be used with my invention.

My invention as will presently become apparent may be used with any number of different 105 kinds of boxes and used for packing various different articles. The present embodiment of my invention illustrated and described in this application is used for packing fabric articles, such as underwear or similar garments, and is particu- 110

larly adapted to be used with boxes in which the garments are laid relatively flat and inserted end-wise into the box.

The particular box illustrated in this application is shown in detail in Fig. 12, and is indicated in its entirety at 9. This box comprises a back 10, a front 11, and side walls 12 and 13 all formed from a single piece of material and glued or pasted together in any suitable manner. One end 10 of the box indicated at 14 may be closed in any suitable manner as by flaps glued or pasted together. The other end of the box is adapted to be closed through a flap 15 extending the entire width of the box and issuing outwardly from the back 10. This flap is provided with a tab 150 adapted to be inserted into the box proper. In addition two side flaps 16 and 17 are provided which extend outwardly from the sides 12 and 13. These flaps may be of any suitable length though 20 in the formation of the box in the most economical manner, said flaps are usually of the same length as the flap 15. Along the top 11 of the box is formed another flap 18 which is folded along the line 19 and constructed with a tab 20. This flap is preferably of a width considerably less than the width of the box and the tab 20 is adapted to be inserted into a slot 21 in flap 15 when the flaps are folded in position. In closing the box, the flaps 16 and 17 are first turned in and the flap 15 25 folded upon the same with the tab 150 extending into the box. The flap 18 is next folded over the other flaps and the tab 20 inserted into the slot 21 holding all of the flaps in closed position.

21 The device for inserting the articles into the
35 box 9 is best shown in Figs. 1, 5 and 7. This de-
vice comprises a base 22 which may be con-
structed of wood or some other suitable material.
When the base 22 is constructed of wood the same
is preferably covered at one end thereof with a
40 plate 29 of sheet metal which extends completely
across the same. Upon this plate is disposed two
angle members 23 and 24 which are spaced from
one another a distance equal to the width of the
box to be employed and which form abutments
45 for holding the box in position. These angle
members may be secured to the base through
screws 25 or through any other suitable means,
which pass through the flanges thereof and
through the plate 29. A similar angle member
50 26 extends between the two angle members 23
and 24 and serves as a stop for retaining the box
in proper position when the articles are packed
within the same. This angle member may be
attached to the base 22 by screws 31 the same as
55 the other angle members. In the use of the de-
vice, the box 9 is placed between the abutments
23 and 24 and against the stop 26 and is so re-
tained while the same is being packed.

Extending in the same direction as the abutments 23 and 24 I provide two angle iron guides 27 and 28 which are provided with upwardly extending flanges 29 and with flanges 30 adapted to overlie the base 22. The flanges 30 are preferably received in grooves 32 formed in the base 22 and face one another. The flanges 29 of the guides 27 and 28 lie inwardly of and parallel with the inner surfaces 33 of the abutments 23 and 24 and are spaced a short distance from the surfaces thereof for a purpose to be subsequently more fully described in detail. Upon the base 22 and to the left of the plate 29 when the device is viewed as in Fig. 7 are disposed two parallel plates 34 and 35 which overlie the flanges 30 of the guides 27 and 28. These plates are attached to the base 22 through screws 36 and 37.

of which the screws 37 pass through the flanges 30 of the guides 27 and 28 and serve to hold said guides in rigid position. The plates 34 and 35 are spaced from one another as designated at 38 and the spaced portions of these plates overlie a groove 39 in the base 22 coextensive with the length of said plates to form a T slot 40 having a function to be presently described in detail.

In mounting the box, the same is placed between the abutments 23 and 24 and against the stop 26 with the bottom 10 thereof lying directly upon the plate 29. In order to hold the various flanges of the box in place, a number of devices are used which will now be described in detail. For the purpose of retaining the flap 15 in open position, the base 22 at the ends of the guides 27 and 28 is slightly depressed or formed with a transverse beveled groove 41. At such locality the extreme end 42 of the plate 29 is bent to follow along the depression or groove 41 and reaches down to the lower end thereof. The ends of the plates 34 and 35 adjacent the groove 41 are doubled back upon themselves as indicated at 43 in Fig. 7 to overlie the extreme end of the portion 42 of the plate 29. The doubled over part 43 of the plates 34 and 35 are preferably on a slant with respect to the portion 42 of the plate 29 and is spaced therefrom so that said parts form a groove 44 for the reception of the extreme end of the flap 15. In inserting the box in the device, the flap 15 of the box is placed between the abutments 23 and 24 and slid along until the free edge of the flap 15 engages within the grooves 44. The box may then be dropped in position behind the stop 26.

For the purpose of guiding the flap 15 into the groove 44, the two extreme ends of the flanges 29 of guides 27 and 28 are formed with upwardly curved edges 45 which assist in directing the flap 15 as the same is moved along the portion 42 of plate 29. The flap 15 is further directed into said groove through the rounding of the plates 34 and 35 formed by the doubled over portion 43 thereof.

The side flaps 16 and 17 of the box 9 are held in position by the following construction. The abutments 23 and 24 are preferably constructed as castings and immediately beyond the ends of the guides 27 and 28 are formed with depressions or angular pockets 46 and 47. In these pockets are disposed leaf spring fingers 48 and 49 which are secured to the abutments 23 and 24 within said pockets through screws 50. The fingers 48 and 49 are normally sprung outwardly from the surface 33 of the abutments 23 and 24 to leave grooves 51 and 52 therebetween into which said flaps may be directed upon inserting the box into the device. When the flaps 16 and 17 lie between these fingers as shown in Fig. 7 said flaps are retained in open position.

For holding the flap 18 and the top 11 of the 135
box 9 in open position, a structure is employed
which is best shown in Figs. 5, 7 and 8. To the
upper portions of the abutments 23 and 24 are
attached through screws 53 two leaf springs or
arms 54 and 55 which extend upwardly therefrom
as most clearly shown in Fig. 6. These arms
have mounted upon the extreme ends thereof a
transversely disposed round rod 56 which is at-
tached to said arms through screws 57. Upon the
central part of this rod is secured a U-shaped 145
spring clip 58 having an upper portion 59 and
a lower portion 60. The upper portion 59 is at-
tached to the rod 56 through screws 61 while
the lower portion 60 thereof is normally in en-
gagement with the rod 56 and extends down- 150

wardly below the same forming therewith a V-shaped groove 156 into which the flap 18 of the box may be inserted.

In order to support the portions of the top 11 of box 9 between the flaps 16, 18 and 17, two additional spring clips 62 and 63 are employed similar to the spring clip 58 but of considerably shorter dimensions. These clips as best shown in Fig. 6 are formed with underlying edges 64 spaced 10 from the bottom of the rod 56 to leave a groove 65 therebetween. When the box is placed within the device, the extreme edges of the top 11 are received within these grooves at the same time that the flap 18 is received within the member 58. 15 It will readily be comprehended that when the box is inserted into the device, the various flanges may be directed into the respective grooves for the reception thereof so that said flanges and the walls of the box are held in open position permitting of the insertion of the articles into the 20 box by endwise sliding movement thereof through the open end of the box.

In conjunction with the box 9 I employ a support for the articles to be packed within the box which is indicated in its entirety at 71. This support is constructed with flanges 69 and 70 formed by scoring the cardboard at its edges along lines 167 and 168. The cardboard is preferably bent to cause flange 69 to extend outwardly at right angles to the body of the cardboard proper and to cause the other flange 70 to extend parallel with said support and offset with respect to the flange 69. These flanges serve to retain the support in proper position with respect to the guides 27 and 28, when the support is moved along the same.

Although my invention as previously stated may be used with various different articles, I have shown in this application an undergarment 40 66 having a lower portion 67 and an upper portion 68 all of well known form. Where a garment of this nature is to be packed in the box, the garment is laid upon the two plates 34 and 35 in a manner best shown in Fig. 1. Upon the 45 middle of the garment is next placed the cardboard support 71 which extends completely across said garment and the guides 27 and 28. In carrying out the method of the invention, the lower portion 67 of the garment is first folded upon the support 71 and then with the upper portion 68 folded to overlie said support and the lower portion 67. Said support together with the garment is thereafter slid along the guides 27 and 28 and directed into the box proper.

50 For the purpose of sliding the support 71 together with the article carried thereby into the box 9, I employ a plunger indicated in its entirety at 72. This plunger is guided for movement along the guides 27 and 28 through two screws 73 which extend through a strip of metal 74 disposed within the T slot 40 which is best shown in detail in Fig. 9. By means of this construction the plunger 72 is slidably mounted and with a minimum amount of friction so that the same 55 may function to move the package along the guides 27 and 28. If desired, the plunger 72 may be provided with a handle 75 by means of which the same may be more readily manipulated. Due to the fact that the slot 40 extends throughout the length of the device, the plunger 72 may be entirely removed therefrom whenever desired.

57 The cardboard support 71 before being inserted into the box 9 is bent along the score marks 168 thereof to cause the flange 70 to lie parallel to the flange 69 and at right angles to the body

of the support to provide two runners for guiding the support into the box and for retaining the article and support in proper position within the box. When so disposed, the flange 70 is adapted to abut against the side walls 12 and 13 of the box and to hold the support medially disposed between the top 10 and bottom thereof. When the article is mounted upon the support, the article is held suspended within the box so that the same is protected through the walls of the box structure.

For the purpose of bending the flange 70, a construction is employed which is best shown in Figs. 5, 7 and 8. As previously stated, the abutments 23 and 24 extend along the guides 27 and 28. At the ends of these abutments, the same are constructed with formers 76 and 176, one for each of said abutments. These formers being identical except that one is right handed and the other left handed only former 76 will be described in detail. This former is constructed with an outer surface 81 which is substantially parallel to the base 72 at the extreme end 77 thereof and is at substantially right angles thereto at the portion 78 of said former adjacent the pocket 47. 100 This surface gradually twists or winds throughout its extent so that the flange 70, which normally lies parallel to the base 22, may be gradually bent upwardly and brought to a right angle position as the support is moved along the guides 27 and 28. Across the pockets 46 and 47 and the vertical portion 78 of the formers 76 and 176 extend keepers 82 which serve to hold the various parts in proper position and also help to guide the formed flange into the box proper.

Cooperating with the formers 76 and 176 are complementary formers 83 and 183 similar in construction. Due to their similarity only former 83 will be described in detail. This former is in the nature of an angle which is constructed with a flange 84 overlying the surface 81 of the former 76 and with a depending flange 85 disposed between the former 76 and the guide 28. The flange 84 lies flush with the keeper 82, while the flange 85 is curved as indicated at 86 tapering from a point at the extreme end to a width near the keeper 82 slightly less than the distance between the flange 84 and the base 22 for a purpose to be presently explained. The former 83 is attached to the base 22 through screws 87 which pass through legs 88 integrally connected to said former. In addition to these screws, other screws 89 extend through the flange 84 and are screwed into the former 76.

In the carrying out of the method of my invention, the support 71 is first folded along the score marks 167 and 168 so as to cause the flanges 69 to extend out from the body of the support substantially at right angles thereto and the flange 70 to extend out from the flange 69 in similar manner. The garment 66 is next placed upon the base 22, support 71 placed across the same as shown in Fig. 1 with the flanges 69 riding along the guides 27 and 28 and the portions 67 and 68 of the garment folded over the support as shown in Fig. 2. When so disposed, the flange 69 extends substantially at right angles to the base 22 and the flange 70 substantially rests upon said base as brought out in Fig. 2. The plunger 72 is next manipulated through the handle 75 and brought against the end of the support 71 and the garment 66 placed thereon and the entire structure moved by said plunger toward the formers 76 and 83. As soon as the flanges 69 and 70 reach this part of the device, the flange 145 150

69 follows between the flange 85 of the former 83 and the flange 29 of the guide 28. At the same time the flange 70 is moved upon the portion 77 of the surface 81 of the former 76. As the support continues to move toward the box 9, the flange 70 follows along the twisted surface 81 of the former 76 and is gradually elevated. Fig. 10 shows the relation of the parts as the elevation of the flange 70 commences. In Fig. 11 the disposition of the parts is shown with the flange 70 further elevated. When the structure reaches the portion 78 of the surface 81 of the former 76 the flange 70 is disposed at right angles to the base 22 and the body of the support and parallel with the flange 91. It is to be noted that the flange 85 of former 83 terminates when the surface 81 indicated at 78 becomes at right angles to the base 22 so that the flange 70 of the support 71 may lie in close contact with the flange 69. The parts when so disposed are clearly shown in Fig. 9 and the function of the keeper 82 to hold the flange in position is clearly brought out in this figure. As the support is further moved along the guides 27 and 28, the flanges 70 are progressively formed and bent in erect manner and the support directed into the box proper. As soon as the flange 70 passes the portion 78 of the surface 81 of the former 76, the same engages the spring fingers 48 and 49 which direct the runners formed thereby into the box. At the same time, the upper portion of the garment may engage the portion 60 of member 58 and the corresponding portion 64 of members 62 and 63 to guide the support with the garment thereon into the box. During the insertion of the support and article into the box, the member 26 previously referred to serves as a stop for preventing the movement of the box away from the various members for holding the flaps in open position. By reciprocating the plunger 72, the full amount, the support 71 with the garment 66 applied thereto may be completely inserted in the box. Thereafter it is merely necessary to remove the box by lifting the same outward from the base 22 at the end thereof of adjacent the stop 26 and close the flaps 16, 17, 15 and 18 in the requisite manner. It is to be noted in Fig. 2 that the flanges 70 of the support 71 are slightly longer than the body thereof. This provides a space for the portion of the garment turned over the edges of the support and serves to hold the support immovable within the box through contact with the protruding ends of said flanges and independent of the garment. It can readily be comprehended that the packing of the articles within the box can be rapidly effected due to the simultaneous bending of the flanges and insertion of the supported article into the box. When the support is within the box the spring of the flanges 69 and 70 causes the flange 70 to lie snugly against the side walls 12 and 13 of the box so as to hold the support immovable in that direction. The flange 70 is preferably constructed of a height equal to the height of the box with the ends thereof limiting the movement of the support 71 toward and from the front and back 10 and 11. The flange 69 is preferably half the size of the flange 70 so that the support 71 is medially positioned within the box.

article carried thereby. The flanges for engagement within the box are automatically bent upon insertion of the support into the box. The device can be constructed at a nominal cost, is very simple to operate, and will not readily get out of order. 80

Changes in the specific form of my invention, as herein described, may be made within the scope of what is claimed, without departing from the spirit of the invention.

Having described my invention, what I claim as new and desire to protect by Letters Patent is:

1. A device for packing articles in boxes adapted to be opened at one end comprising a base, means for supporting a box upon said base with the end thereof open, a guide on said base for slidably supporting a cardboard support adapted to support an article to be inserted into said box, forming means on said base adapted to engage the ends of said cardboard support and to bend flanges thereon serving as runners for engagement with the interior of the box to hold the support immovable within said box, and a plunger slidable along said guide for moving said support along said forming means to form the runners thereon and to insert the support and article within the box. 90 95 100

2. A device for packing articles in boxes adapted to be opened at one end comprising a base, means for supporting a box upon said base with the end thereof open, a guide in said base for slidably supporting a cardboard support adapted to support an article to be inserted into said box, forming means on said base adapted to engage the ends of said cardboard support and to bend flanges thereon serving as runners for engagement with the interior of the box to hold the support immovable within said box, and means for retaining the formed runners on said support in formed position prior to the entrance of the support into the box.

3. A device for packing articles in boxes having flaps at one end adapted to be folded into open or closed position, comprising a base, means on said base for receiving and retaining a box at 120 a predetermined position, a lip for supporting one of the flaps of said box to hold the same in open position, means for supporting the other flaps of the box in open position, and means for sliding the article along said lip and into the box. 125

4. A device for packing articles in boxes having flaps at one end adapted to be folded into open or closed position, comprising a base, abutments formed on said base for holding a box in a pre-determined position upon said base with the bottom of the box overlying said base, a bar extending across said box near the open end thereof and supported on said base, and a spring finger carried by said bar and adapted to receive and support the upper flap of said box to hold the same in open position, means for supporting the other flaps of the box, and means for inserting an article into the box through the open end thereof. 135

5. A device for packing articles in boxes having flaps at one end adapted to be folded into open or closed position, comprising a base, abutments formed on said base for holding a box in a pre-determined position upon said base with the bottom of the box overlying said base, a bar extending across said box near the open end thereof and supported on said base, and a U-shaped spring clip attached at one end to said bar and underlying said bar for the reception of the upper flap of the box, said clip being adapted to hold said flap in open position, means for holding the 150

- other flaps of the box in open position, and means for inserting the article into the box through the open end thereof. 40
6. A device for packing articles in boxes having flaps at one end adapted to be folded into open or closed position, comprising a base, abutments formed on said base for holding a box in a predetermined position upon said base with the bottom of the box overlying said base, a pair of spring fingers lying along said abutment and having the free ends thereof adapted to engage the side flaps of the box to hold the same in open position, means for holding the other flaps of the box in open position, and means for inserting articles into the box through the open end thereof. 45
7. A device for packing articles in boxes having flaps at one end adapted to be folded into open or closed position, comprising a base, abutments formed on said base for holding a box in a predetermined position upon said base with the bottom of the box overlying said base, means forming a slide for slidably supporting a support for an article to be inserted into the open end of said box, said slide lying substantially in the same plane as the bottom of the box, said base having a depression therein for receiving the lower flange of the box, and a member overlying the extreme end of said depression for engagement with a lower flap of the box to hold the same in open position, means for holding the other flaps in open position, and means for sliding the support for the article along said slide and into the box through the open end thereof. 50
8. A device for packing articles in boxes adapted to be opened at one end comprising a base, means for supporting a box upon said base with the end thereof open, a guide on said base for slidably supporting a cardboard support for an article to be inserted in the box, a downwardly extending former cooperating with said guide and adapted to bend a flange on said support, a downwardly extending former adapted to double said flange back upon itself, and a plunger for sliding said support along said guide to form said flange and insert the support into the box. 55
9. A device for packing articles in boxes adapted to be opened at one end comprising a base, means for supporting a box upon said base with the end thereof open, a guide on said base for slidably supporting a cardboard support for an article to be inserted in the box, a former in the shape of an angle attached to said base and having a leg extending downwardly from and in spaced relation to said guide, said leg being gradually tapered to bend a downward flange on said support, and a former cooperating with said first named former having a surface tapered upwardly from said base and gradually changing angularity from a horizontal to a vertical direction and cooperating with said other former to bend said flange back upon itself, and a plunger slidably mounted along said guide for forming the flange on said support and for sliding said support into the box. 60
10. The method of packing fabric articles in boxes having an open end which consists in placing an article upon a base and in between two guides formed thereon, in placing a cardboard support upon said article, in folding the article about the cardboard support and retaining a box upon said support with the open end thereof in alignment with the guides, in forming runners on the edges of said support, and in sliding the support with the article thereon into the box to cause the runners thereof to engage the box and hold the article supported within said box. 65
